(57) **CLAIM**

The ornamental design for a desk lamp with articulating arm, as shown and described.

DESCRIPTION

FIG. 1 is a front perspective view of a desk lamp with articulating arm showing my new design with a desk top base;

FIG. 2 is a back perspective view thereof;

FIG. 3 is a front elevational view thereof;

FIG. 4 is a rear elevational view thereof;

FIG. 5 is a side elevational view thereof, the opposing side elevational view being a mirror image thereof;

FIG. 6 is a top plan view thereof; and

FIG. 7 is a bottom plan view thereof;

FIG. 8 is a front perspective view of a desk lamp with articulating arm showing my new design with a desk top base and external wiring;

FIG. 9 is a back perspective view thereof;

FIG. 10 is a front elevational view thereof;

FIG. 11 is a rear elevational view thereof;

FIG. 12 is a side elevational view thereof, the opposing side elevational view being a mirror image thereof;

FIG. 13 is a top plan view thereof; and

FIG. 14 is a bottom plan view thereof; and

FIG. 15 is a front perspective view of a desk lamp with articulating arm showing my new design with a clamp base and external wiring;

FIG. 16 is a back perspective view thereof;

FIG. 17 is a front elevational view thereof;

FIG. 18 is a rear elevational view thereof;

FIG. 19 is a side elevational view thereof, the opposing side elevational view being a mirror image thereof;

FIG. 20 is a top plan view thereof; and,

FIG. 21 is a bottom plan view thereof.
